SHOE WITH SHANK SPRING AND
STIFFENER

Harry H. Johnson, Brookline, Mass.

Application August 31, 1946, Serial No. 694,289

2 Claims. (Cl. 36—76)

1

This invention relates to an improvement in the shoe-making art. The application is a continuation-in-part of my copending application, Serial No. 627,163, filed November 7, 1945, now abandoned.

In conventional footwear such as is commonly worn by men and women in this country, the sole structure comprises a ball portion, a shank portion and a heel portion. The ball portion usually has a substantially plane tread surface extending from the forward extremity or toe of the sole to the break line or juncture of the ball and shank portions. The shank portion of the sole structure is usually inclined with respect to the ball portion and rises rearwardly to the heel portion which is maintained in a relatively elevated position by a heel member formed on or attached to the under side thereof. The heel member has a tread surface which is in a common plane with the tread surface of the ball portion when the footwear is in its normal or ordinary position, that is, the position assumed when a shoe tree is fitted therein or when the footwear is on a foot and the wearer is in an ordinary standing position on a horizontal surface. The sole structure is usually flexible at the break line so that during walking, running, or the like, the sole flexes at the break line to increase the inclination of the shank portion with respect to the ball portion during a part of each step. Many articles of footwear for men and women are equipped with rigid shank stiffeners which are built into the shank and heel portions of the sole structure and usually extend forward nearly to the break line thus preventing sagging of the arch, helping to keep the heel member at the proper angle to the shank portion of the sole, but not interfering with the flexing of the sole structure at the break line. In ladies' shoes, the forward end of the shank stiffener sometimes wears through the outer sole.

According to the present invention, a flexible resilient spring is inserted in the sole structure to underlie the forward portion of the shank stiffener and to extend forward past the break line and into the ball portion of the sole. This spring is shaped so that its rear portion which underlies the shank stiffener presses upward against the shank stiffener and tends to flex the sole at the break line. The spring also effectually prevents the forward end of the shank stiffener from wearing or punching through the sole. The physical characteristics of the spring, including strength and resilience, are selected so as to produce the desired degree of upward pressure against the shank stiffener. The shank stiffener

2

is usually secured at its rear end to the heel portion of the sole, and in some cases is also secured at its forward end to the sole. In either event, the flexible spring tends to lift the shank and heel portions of the sole to a steeper inclination with respect to the ball portion, and to operate with the shank stiffener as a compound lever as hereinabove described. When the shoe is worn, the shank and heel portions of the sole are held against the foot of the wearer at all times, whether the wearer is standing, walking, running or engaging in any other form of activity.

For a more complete understanding of the invention, reference may be made to the following 15 description thereof, and to the drawing, of which:

Figure 1 is a side elevation of a shoe embodying the invention with the wearer's foot therein, a portion being broken away to show in section;

Figure 2 is a bottom plan view of the same;

Figure 3 is a section on the line 3—3 of Figure 2;

Figure 4 is a perspective view of the spring shown in Figures 1, 2, and 3;

Figures 5 and 6 are perspective views of modified forms of the spring.

The invention is shown in Figure 1 as embodied in a woman's shoe of the "sling back" type consisting of a sole structure 10 and an upper 12 which is open at the heel. The sole structure 30 comprises an outer sole 20, an inner sole 22, a sock lining 24, and a heel member 26 which is attached to the heel portion of the outer sole. Between the outer sole and the inner sole is a conventional shank stiffener 30 secured at the heel 35 end by a suitable fastener 32 and extending from the heel portion of the sole forward nearly to the break line 34 of the sole. As indicated in Figure 3, the stiffener 30 is made with a longitudinal crimp 36 extending for most of its length and 40 forming a longitudinally extending rib therein which materially stiffens the member and makes it substantially rigid. According to the present invention, a flexible resilient spring element 40 is built into the sole structure as indicated in Figures 1, 2, and 3. This element consists of a piece of strong spring metal which is preferably from 0.010" to 0.020" thick, this being somewhat thinner stock than that of which the stiffener 30 is made, and suitably tempered to be highly resilient.

45 In men's shoes and working shoes, heavier stock up to 0.030" or more can be used. The element may be cut from a strip of spring steel or other spring metal or may be cut out of a sheet of such metal, and is of sufficient length to extend from 50 a point well forward of the break line in the

ball portion of the sole to a point in the shank portion of the sole near the heel. If, as illustrated in Figure 3, the shank stiffener 30 is made with a longitudinal rib 36, the portion of the spring 40 which underlies the ribbed portion of the shank stiffener is also preferably crimped as at 42 so that a part of the spring 40 has a longitudinal rib fitting against the rib 36 of the shank stiffener 30. This helps to maintain the spring 40 in its proper position within the sole structure. In assembling the sole structure on a last, the forward portion 45 of the spring 40 may be secured to the ball portion of the inner sole 22 by any suitable adhesive or by a fastener such as a tack 46. The forward end portion of the spring 15 may also be adhesively secured to the outer sole, if desired.

As shown in Figure 4, the spring 40 is made with a bend as at 44 so that the rear portion of the spring is inclined with respect to the forward portion, the angle of inclination being materially steeper than the angle of inclination of the shank of the sole structure with respect to the ball portion of the sole structure when the shoe is in its ordinary normal position, that is, the position which it assumes when it is being worn and when the wearer is in an ordinary standing position with the tread surfaces of both the sole and heel of the shoe resting on the ground.

Since the angle of inclination of the rear portion of the spring 40 with respect to the forward portion thereof is steeper than the corresponding angle in the shoe itself, the effect of installing the spring 40 in the shoe structure in the manner shown in Figure 1 is to elevate the shank and heel portions of the sole structure to a steeper than usual inclination with respect to the ball portion of the sole. The amount of bend of the spring 40 is preferably sufficient to cause the shank and heel portions of the sole to assume an angle of inclination as great as the maximum angle occurring when the shoe is worn during walking, dancing or running. Hence, when the shoe is worn, the spring 40 acts to maintain the shank and heel portions of the shoe against the foot of the wearer at all times. This function of the spring is important because when shoes, slippers or pumps are open or loose at the heels and are not provided with such springs, the rear part of the sole structure usually loses contact with the foot of the wearer when the foot is flexed as in walking and the like.

The spring 40 also has an additional function which is highly important, especially to those who have a tendency toward fallen arches or flat feet. The upward pressure of the rear portion of the spring 40 against the forward portion of the shank stiffener 30 which it underlies tends to rock the shank stiffener upward about its rear end as a fulcrum. The forward portion of the shank stiffener, in turn, presses upward against the portion of the inner sole adjacent to the break line and thus resiliently supports the arch of the foot at a zone where sagging of the natural arch of the

foot often occurs. Since the forward end portion of the shank stiffener is approximately midway between the adjacent side edges of the sole, it tends to support and elevate the longitudinal arch of the foot. Thus the shoe in which the spring 40 is built in underneath the shank stiffener is not only comfortable to wear but also results in corrective support of fallen or sagging arches.

Instead of being shaped, as illustrated in Figure 10 4, from a sheet of spring metal, the spring may be forked as illustrated at 47 in Figure 5. This form is desirable in men's shoes which have considerable width, the forked shape 47 of the forward portion permitting a certain amount of twisting action in the spring which provides a degree of freedom of action of the sole structure.

A simpler form of spring is shown in Figure 6, this form consisting of a strip 48 of spring steel with an intermediate bend and, if desired, a crimped rib 42 in its rear portion to nest with the crimped rib 36 of the shank stiffener 30.

To fasten the forward end portion of the spring 47 or 48 to the innersole 22 or outer sole, a suitable adhesive may be used, or, as indicated at 20 25 49 in Figure 6, a piece of adhesive tape may be wrapped about the forward portion. Any of the springs shown on the drawing can be assembled in the sole structure without any fastening means, but the use of some fastening means is convenient 30 to keep the spring properly in place when the outer sole 20 is being applied.

I claim:

1. In an article of footwear, a sole structure which has ball, shank and heel portions, a rigid shank stiffener secured at one end to the heel portion of the sole structure and extending forward on the shank portion, and a flexible resilient member in said ball and shank portions, the rear part of said member underlying the forward part 35 of said shank stiffener, the forward end of said member extending into the ball portion of the sole structure, said member having a bend between its forward and rear parts and being of such a strength as to resiliently maintain said shank and heel portions of the sole structure at a materially steeper angle of inclination with respect to said ball portion than the corresponding angle in an ordinary shoe of the same size and style when off the foot, whereby when said footwear is worn said flexible resilient member inherently presses upward against said shank stiffener so as to hold the shank and heel portions of the sole structure against the foot at all times during walking and the like and inherently tends 50 to elevate the shank and heel portions of the sole structure.

2. In an article of footwear, a sole structure as set forth in claim 1, in which the shank stiffener is longitudinally bent to form a central rib and the flexible resilient member is formed with a complementary rib in the part thereof underlying the shank stiffener.

HARRY H. JOHNSON.
